UNITED STATES PATENT OFFICE.

CARL H. BUHL, OF CLEVELAND, OHIO.

RAILWAY SIGNALING SYSTEM.

1,253,208.

Specification of Letters Patent. Patented Jan. 15, 1918.

Application filed July 22, 1912. Serial No. 710,768.

To all whom it may concern:

Be it known that I, CARL H. BUHL, a citizen of the United States, residing at Cleveland, in the county of Cuyahoga and State 5 of Ohio, have invented certain new and useful Improvements in Railway Signaling Systems, of which the following is a specification.

My invention relates to a railway signaling system, and the invention consists in the improved electrical signaling means substantially as hereinafter shown and described and more particularly pointed out in the claim.

15 The object of the invention is to provide electrical means to automatically illuminate a green light in the cab of an engine when another train occupies the same track within two given blocks in advance thereof, there- 20 by giving a cautionary signal of danger ahead; and, by the same means cause a red light to be illuminated in the cab when the track is occupied in the block directly ahead, thereby giving a danger signal. These same 25 results are also produced by my invention when a break occurs in the rails, when a switch is left open, when another train crosses the track, and when the electric current weakens or fails at its source or by dis- 30 connection or break in the connecting wires. When the track is clear, the object also is to provide means for the constant illumination of a white light in the cab of the engine, and the inventive concept also includes the plac- 35 ing of similar signaling devices at fixed stations along the line, as at switching and crossing points, to give warning of the approach of trains when one and two blocks away from the station. The invention also 40 embodies a sounding device to give an audible signal in the event of injury to the signal lamps, particularly the red or danger light.

In the accompanying drawings, Figure 1 45 is a diagrammatic view of a single track railway divided into blocks and provided with my invention, this view showing a clear track for a train represented by a set of wheels in the first block at the right.

50 Fig. 2 is a diagrammatic view corresponding to Fig. 1, but showing two trains in two adjoining blocks and another train farther removed, and illustrating the operation of the devices in giving both cautionary and 55 danger signals to the oncoming train.

Fig. 3 is a diagrammatic view of the in-

vention with switch and station signal devices in coöperating relations with an approaching train in the second block from the switch, both the green caution lights in the 60 cab and at the station being illuminated.

The invention contemplates the use of a signaling device A in the engine cab, and also a similar device A' at stations along the railway, as at a switch S, see Fig. 3. These 65 devices each consist of an electro-magnet having a soft iron core 2 of the usual horse-shoe form, each core having a double winding, one of which is of finer wire and more turns than the other. A tilting armature 3 70 having its pivot or fulcrum between its ends is mounted opposite the core extremities on a vertical bar 4 secured to the cross-piece 5. Bar 4 is a permanent magnet to give the armature the same polarity as one of the 75 cores, and as poles of like polarity repel each other, the armature will be constantly repelled at one or the other of the poles of the electro-magnet when the current is flowing, dependent upon the direction of the electric 80 current through the coils, and it also follows that the unlike poles will be attracted accordingly. Briefly, the object is to make armature 3 a permanent south-pole and by reversing the flow of the electric current, 85 change the poles of the magnet as occasion requires so that the resultant north pole will tilt the armature on its pivots either to one side or the other and thereby cause a flow of the electric current through either one or 90 the other of two signal lamps W or G, the first being a white light and the second a green. A third lamp R giving a red light is also placed in the electrical circuit by device A, but only when the other two lights 95 are cut off. For this purpose, a spring strip 6 mounted on the armature at one side thereof and insulated therefrom extends beyond both armature ends to engage two fixed contacts 7 and 8 in the red lamp circuit; but this 100 contact only occurs when the armature is balanced and not under the influence of either one of the poles of the electro-magnet. The spring ends of the strip 6 maintain the armature in the balanced position until the elec- 105 tro-magnet is energized. A third contact 9 on one side of the pivot of the armature is engaged by the armature to close the electrical circuit for the green light, and a fourth contact 10 on the left side closes the 110 white light circuit when the armature is tilted up on that side. Tilting of armature

3 occurs when electric current is caused to flow in either one direction or the other through the heavier and shorter winding 13 of device A, which winding is connected by a wire e leading to the axle or frame E of the engine, and by a wire 20 leading to brush 16.

All three lights have a wire connection 11 with one terminal of a local battery 12 carried by the engine, the other battery terminal being connected by wire 14 with the bar 4 of device A. Contact 7 is connected by wire 15 with wire 14, and contact 10 is connected by a wire 18 with the fine winding 19 on the right core of the electro-magnet, and which winding is extended and includes a like winding on the left core with a wire f leading therefrom to the green light G, reference being had to Fig. 2. A wire 21 also leads from the cross connecting wire of the coils 19 to a fixed contact 22 which is normally engaged by the armature 23 of a magnet 24, this armature being electrically connected with the local battery circuit as represented by wire 11. The coil of magnet 24 is connected by a wire 25 with a second brush 27 engaged with the track T, and also by a wire 26 with wire e leading to the metal frame or axle E of the engine. The brushes 16 and 27 have sliding engagement with the two track rails which are insulated one from another. Track T is divided into blocks of any given length, say one mile, each block being insulated from the other blocks; and these blocks are each subdivided to provide short pick-up sections 28, 28' oppositely in the two rails thereof. These sections are of about six feet in length, more or less, and insulated from the remaining rails in the block, of which they form a part. The several long blocks are designated in the drawings by a, b, c, and d, all being alike in arrangement and electrical connections.

The track devices and circuits for each of the respective blocks comprise two plural-contact relays L and M, and one single contact relay N, the first two being hereinafter referred to as the "first block" and "second block" relays, respectively, and the relay N as an "emergency relay." These relays are preferably of the "mercury" kind, and the drawings are merely diagrammatic of any suitable style or kind, using single or double armature. The first block relay L serves to place the red light in commission, and the second block relay M either the white or green light. The emergency relay N is used to open the track circuit when the electric current becomes too weak to operate device A, thereby establishing a red signal in the advancing train to indicate a dangerous condition in the block ahead. The three track relays are jointly housed in a suitable receptacle located at the side of the track, and the wires leading thereto are either sup-

ported by poles along the track or placed in conduits.

Now tracing the electrical circuits for the track devices, and referring to block a Fig. 1, wire 30 leads from the short pick-up section 28 to a fixed contact 31 opposite armature 32 of the first block relay L. The pick-up section 28' has a wire connection 33 leading to armature 34 of the second block relay M, and the armature 35 at the right 75 of this same relay M is connected by wire 36 with the track rail in block a which is engaged by brush 27 in its travel. The opposite track rail of this block has a wire connection 37 leading to the armature 38 of 80 emergency relay N, including a battery 39; and a contact 40 for armature 38 is connected by a wire 41 with the end portion of track T engaged by brush 27 in block a.

The electrical connections between the respective relays are as follows:

The relays L and M are diagrammatically represented as having two armatures and two contacts for each armature, but in practice the desired results would be obtained by 90 the use of a single armature. The present showing is for greater clearness as it permits a separate grouping of the contacts. Thus, the contact 42 opposite contact 31 of relay L has a wire 43 leading to the left 95 contact 44 of armature 34 of relay M. The right contact 45 opposite armature 34 has a wire connection 46 with the right contact 47 of the other armature 35 of this same relay M, and the opposite contact 48 for armature 35 is connected with contact 44 by a wire 49. Contact 47 also has a wire 50 leading to relay L where it connects with a contact 51 normally engaged by the right hand armature 52 of said relay. A contact 53 on 100 the opposite side of armature 52 connects by a wire 54 with wire 36, and said armature 52 is connected by a wire 55 with the negative side of a battery D. The positive side of the battery has a wire connection 56 leading to the left armature 32 of relay L, and a resistance coil 57 is placed in this line of connection to prevent a short circuit of the battery when the track pick-up sections 28, 28' happen to be occupied by a standing 115 train. The emergency relay coil N cross-connects with wires 55 and 56 by wires 58 and 59 respectively.

The coil of relay L in block a and the corresponding relay for each successive block, 120 is electrically in circuit with one track-rail of the immediate block ahead, as indicated by wire 60; and the other connection to place this relay L in circuit is by wire 61 which extends to the relay M in the preceding block as shown in Fig. 1 between the blocks b and a, or c and b. Correspondingly, each relay M has its other wire connection 62 extended forwardly along 125 the track to the second block in advance of 130

the block it represents, as shown in Fig. 1 between blocks *a* and *c*, or blocks *b* and *d*. Wire 62 connects with the track rail which is adapted to be engaged by brush 27. The track devices and electrical circuits above described connect all of the respective blocks *a*, *b*, *c*, etc., in like manner to establish circuits in signaling the engineer in his cab of any obstruction or danger in the track one and two blocks ahead.

In operation, a clear track is indicated by the white light *W*, and the various devices and electrical circuits are related as shown in Fig. 1. The train or engine *E* is herein shown as occupying block *a* and as establishing an electrical circuit between the two tracks in this block, including brush 16, battery *D*, and the winding 13 of electro-magnet device *A*. This circuit is the "white light circuit" and may be traced from track *T* by the wires and parts designated as follows: 36, 35, 48, 49, 44, 43, 42, 32, 56, 57, *D*, 55, 52, 51, 50, 47, 46, 45, 34, 33, 28', 16, 20, 13, *e* to *E* and to the place of beginning at 36. When brush 16 engages pick-up division 28' of the track, the result is to energize electro-magnet *A* through coil 13 and thereby tilt its armature 3 into engaging position with contacts 10 and 7 as shown in Fig. 1. Contact at 7 is however ineffective in view of the retirement of strip 6 from contact 8 at the other end of the armature, and moreover it must be remembered that this strip is insulated from the armature and that it makes no contact with the poles. Contact relations at 10 establishes a local circuit for lamp *W* over wire 11 to battery 12, bar 4 and the armature 3. A locking circuit is also established to lock armature 3 in tilted position, this result being accomplished by permitting the electric current to flow through the right-hand coil 19 of electro-magnet *A* by reason of the contact made at 10, a separate path for a part of the current being provided by wire 18 to this right-hand coil 19 and by wire 21 to contact 22 and armature 23 of release relay 24, to the battery 12 by wire 11, and back to the armature 3 by wire 14 and bar 4. Obviously, when release relay 24 is energized this "locking circuit" for coil 19 is broken, which result follows when either the track relay *L* or *N* is deenergized by occupancy of the tracks by another train or by a break in the track one block ahead or by failure of the electric current.

In Fig. 2 three trains *E* are shown on tracks *T* in blocks *a*, *c* and *d*, respectively to illustrate both caution and danger signaling conditions. Thus, the device *A* of the train in block *a* is placed in circuit to illuminate the green light *G* to show that the block *c* is occupied, and the device *A* of the train in block *c* shows a red light to indicate the

occupancy of block *d* by the car or train *E* therein. The "green light" circuit is established by a reversal of tilt of the armature 3 of device *A* from that shown in Fig. 1, a result obtained by releasing the armatures 34 and 35 of relay *M* in block *a* to engage contacts 44 and 47, respectively. Release is effected by deenergizing said relay, and the source of electric current for relay *M* in block *a* (and also the relay *L* in series therewith in block *b*), is at battery 39 of block *c*, and the circuit therefor may be traced by wire 62 of this relay *M*, track *T*, wire 41, contact 40 and armature 38 of emergency relay *N* of block *c*, wire 37 to battery 39 and to the opposite track rail of block *c*, and thence to wire 60 leading to relay *L* in block *b* and continuing by wire 61 to the same relay *M* of beginning. However and inasmuch as the block *c* is occupied (as indicated by the train *E*), a short circuit between the double rails is established, thus cutting off the electric current from battery 39 for relay *L* in block *b* and relay *M* in block *a*. The result is as stated, the green light *G* being placed in the lighting circuit of battery 12 by the armature 3 of device *A* engaging contact 9. The path of the illuminating current is traceable from contact 9 over the wire 11 to battery 12 and by wire 14 to bar 4, and the same locking effect on the armature 3 is obtained as before by a division of the electric current over wire 21 to the locking coil 19, but in this instance to the coil at the left and by wire *f* which leads to contact 9.

The "red light" circuit and danger signal is shown in operation in block *c*, Fig. 2, the armature 3 of device *A* for the train *E* in this block *c* being in balanced position with the metal spring strip 6 engaged with contacts 7 and 8 and the armature apart from contacts 9 and 10. The lighting circuit in this instance includes contact 8 over wire 11 to battery 12, and wires 14 and 15 to contact 7, and no electric current is flowing through any of the windings of device *A*. This is the result of the train *E* in the block *d* causing a short-circuit to deenergize relay *L* in block *c*, and incidentally, also relay *M* in block *b*. In establishing the "red light" circuit, the release relay 24 of the device *A* is energized, which opens the "locking coil circuits" controlled by armature 23 and contact 22, and the electric current for this purpose is obtained from the battery *D* in block *c* when brush 27 engages pick-up rail 28. This is illustrated in block *c*, Fig. 2, the electrical circuit being traceable from this pick-up point by the following letters and figures of reference in the order named: 30, 31, 32, 56, 57, *D*, 55, 52, 53, 54, 36, *E*, *e*, 26, 24, and 25 to brush 27, the place of beginning.

In Fig. 3 I show an open switch *S* in the track two blocks in advance of the train *E*, 130

the blocks in this instance being designated by reference letters *g*, *h* and *i*. Thus when the switch *S* is open, the electric current from battery 39 in block *i* is cut off at the 5 contact 63 opposite the arm 64 controlled by the switch, thereby deenergizing relay *L* in block *h* and relay *M* in block *g* and establishing a "green light" circuit for the train in block *g* and a "red light" track circuit in 10 block *h*.

Fig. 3 also illustrates the application of a signaling device *A'*, or a duplicate of device *A*, to station signaling purposes. This device has a green light *G* and a red light *R*, 15 and may also have a white light, but the white light and the locking coils are omitted for the sake of simplicity. As shown, the station device *A'* is electrically connected to a set of relays *I* and *J* along the track, the 20 first relay —*I*— having wire connections 65 with the opposite rails in block *h* of track *T*, which rails are further connected by wires 37 and 41 to battery 39 as already described, and whereby said relay —*I*— is energized 25 when the track in block *h* is not occupied. The second relay *J* is connected by wires 66 and 67 with the rails of the track in block *g* and also with its battery 39 in a similar manner as described, but in view of the fact 30 that block *g* is shown as occupied by train *E* it is at once apparent that the electric current from battery 39 of this block *g* is short-circuited as to relay *J*, thereby releasing its two armatures 68 and 69 and establishing a local battery circuit 70 for energizing the electro-magnet device *A'*, which 35 by the way, is made like the engine device *A* in that it tilts its armature one way or the other dependent upon the direction of 40 flow of the current. Reversal of flow of the electric current is obtained by change in position of the armatures in relay *J*, and when the said armatures are in the dotted positions shown in Fig. 3, the armature 73

of device *A'* is tilted reversely to that 45 shown and both lights *G* and *R* are cut off from electric current. However as shown, the green light *G* is in the local circuit 71 containing battery 72. The red light *R* is placed in this circuit and the green light cut out when block *h* is occupied by the advancing train, as in that event relay —*I*— will become deenergized and the circuit 70 broken to place the armature 73 in a balanced condition and with the outer contacts 55 74 and 75 only in contact with strip 6. Neither one of the two lamps of device *A'* is illuminated when blocks *g* and *h* are unoccupied, but the operator at the switch, crossing, or station will be at once advised 60 when a train is within one or two blocks by the illumination of a red or green light as the case may require.

What I claim is:

In a railway signaling system, a set of 65 electrical selective signaling devices, a compound polarized relay for controlling the selective energization of the signaling devices, electrical circuits for said relay, said relay comprising a permanent magnet, cores 70 supported adjacent the permanent magnet, a cross piece supporting the cores, circuit terminals disposed adjacent the cores, an armature pivotally supported intermediate its length, a spring strip supported by the 75 armature and insulated therefrom, the ends of the spring strip extending beyond the ends of the armature, to balance the armature prior to the energizing of the electro-magnet, and means for automatically completing the circuit to operate the relay, and cause a signal.

In testimony whereof I affix my signature in presence of two witnesses.

CARL H. BUHL.
